CODING AND DECODING APPARATUS

Walter S. Lemmon, New York, N. Y., assignor, by
mesne assignments, to International Business
Machines Corporation, New York, N. Y., a cor-
poration of New York

Application June 16, 1934, Serial No. 730,905

21 Claims. (Cl. 197—4)

This invention relates to apparatus for coding and decoding communications, and has for an object to provide for the rapid and accurate coding and decoding of such communications with a minimum of labor and with no demand upon the operator for a knowledge of cryptography.

It is an object of the invention to provide an apparatus which will automatically code a message as a result of the mere typing of the uncoded message, and which will automatically decode the message as a result of the mere typing of the coded message.

It is a further object of the invention to provide means for changing the code at will. It is a feature that the code can be changed instantaneously so that by prearrangement or otherwise the code may be changed several times in the transmission of a single message, if desired. The illustrative embodiment of the invention includes the following desirable features. The apparatus comprises two typewriters adapted to be interconnected for coding purposes, but also adapted to be separately operated for ordinary office use when not required for coding purposes. The apparatus is effective, when the uncoded message is typed, to produce both a correct writing of the copy and a writing of the same message in code, and, when the coded message is typed, to produce a correct writing of the code message for comparison with the copy and a correctly typed translation of the code message.

It is a further object of the invention to provide an apparatus in which the coded message is automatically divided into equal groups of letters, say five letters to a group, and in which the decoded message, upon the mere copying of the coded message, is caused automatically to appear with the words properly divided and no extra spaces or characters included.

As a part of the mechanism for producing the code message in five letter groups, it is a feature that provision is made of means for automatically producing a space in the secondary machine after every fifth keyboard operation of the primary machine. It is a further feature that the mechanism is so arranged that a printed character will always be produced in the secondary machine by the operation of either a character key or the space bar of the primary machine when coding so that no intended letter group is subdivided into two groups of a lesser number of letters than that intended.

In general, any letter or character struck on the primary machine will produce a definite code or translation letter on the secondary machine,

and this relation involving the same two characters will hold whether the machines are being used for coding or decoding, the two characters being always reciprocally paired for any selected code setting. An exception is made, however, with reference to the space bar and the dash key, the connections to these members in both the primary and the secondary machine being different from the connections to the other character keys. In coding the operation of the space bar produces a particular letter, and in decoding the same letter produces a space in the translation. The same letter, however, produces a dash when coding, and is produced by a dash when decoding. Provision is made of means for instantaneously altering the operating connections between the primary and secondary machines to produce this change in the mode of operation.

It is a further feature that the connections to the keyboard members of the primary and secondary machines are connected in inverse sequence to relatively rotatable contact members. In order that this may not result, however, in too simple a code, or in a too limited variety, both machines include a switchboard arrangement whereby the sequence of letter connections to the circular contact members may be changed as desired so long as the order or sequence upon one circular member is made the exact opposite of that upon the other.

It is a further feature that the apparatus is equipped with means adapting it for operation either from a direct or alternating source of current supply.

It is a further feature that provision is made to render the code changing mechanism inoperative when desired so that there is no danger of an unauthorized person tampering with the machine and ignorantly changing the code without knowledge of the authorized operator.

It is a further feature of the invention to provide means for indicating to the operator that a particular or zero code setting exists in order that he may have a starting basis for setting the machine to any desired code.

Other objects and advantages will hereinafter appear.

In the drawings which illustrate one embodiment of the invention, and which form a part of this specification:

Figure 1 is a diagrammatic view illustrating in part the primary and secondary machines and the operating connections between them;

Figure 2 is a view in sectional elevation, partly broken away, illustrating the commutator or cod-

ing mechanism through which the coding and decoding are accomplished;

Figure 3 is a view in end elevation of the coding rings;

5 Figure 4 is a fragmentary, sectional view taken on the line 4—4 of Figure 2, looking in the direction of the arrows; and

10 Figure 5 is a sectional view taken on the line 5—5 of Figure 2, looking in the direction of the arrows.

15 The coding apparatus as illustrated herein comprises a primary typewriter 1 and a secondary typewriter 2, both of which are desirably of the electromagnetic type. Each typewriter comprises a constantly rotating cylinder 3 which operates cams such as 4 and 5 to produce the actuation of the carriage feed mechanism or the type bars 6 when they are tripped by the space bar 7 or a character key 8. There is one of these cams for 20 each character key and one for the space bar. The character key marked 9 is taken as the "dash" key in both machines for the purpose of this description. The operation of any character key of the primary machine will cause the associated type bar 6 to be swung to a printing position in which the type carried by it strikes against the platen 10.

25 Each shaft 11 is driven from a motor (not shown), the field windings of the motors being connected between conductors 12 and 13. The entire apparatus is operated from a suitable source of line current, either A. C. or D. C., and the motors are of the universal type. The current may be regarded as coming in through a 30 conductor 14, passes thence through a conductor 15 to the conductor 12. After passing through the field windings of the motors the current passes through the conductor 13 and a conductor 16, thence through a control switch 17 and a 35 conductor 18 back to the line.

40 The general construction and mode of operation of the apparatus will first be described without reference to the features peculiar to the space bar and the dash key, and a description 45 of the space-dash feature will then be given. In the primary machine provision is made of a multiplicity of switches 19, each of which is normally open, but adapted to be closed by one of the cams 4 or 5. Taking one of these switches other than 50 that of the space bar or the dash key as illustrative, it will be observed that the closing of the switch which is produced by the actuation of the associated character key completes a circuit as follows: Current coming in through the conductor 55 14 passes through the conductor 15 to a conductor 20, and thence through a resistance 21 to a contact 22. A plug 23 will be inserted between resilient conductors 24 and 25 to spread them apart when the apparatus is connected to a source 60 of D. C. current, and such a setting will be assumed until otherwise stated. The current passes from contact 22 through conductor 24 and a conductor 26 to a terminal 27. From the terminal 27 the current passes through a conductor 28, a conductor 29, a resistance 30 and a conductor 31 to the closed switch 19. The current passes thence through a conductor 32, a plug 33, a conductive socket 34 and a conductor 35 to a conductive ring 36 which is fast upon, but insulated 65 from, a shaft 37. The ring 36 is connected through a conductor 38 with a contact 39 carried by an insulating ring 40 which is also fast upon the shaft 37. There is a multiplicity of such contacts 39, the contacts being equally spaced circumferentially completely around the 70

ring. A commutator ring 41 is mounted on the shaft 37 and has an equal number of contacts which are also equally spaced. The current flows through the contact 39 to the associated contact 42 of the commutator ring, and thence through a conductor 43, a plug 44, a socket 45 and a conductor 46 to the winding 47 of an electromagnet mounted beneath the keyboard of the secondary machine. The electromagnet includes a core 48 which is carried by a stem 49 suspended from one of the key levers 50 of the secondary machine. The core or armature 48 pulls the key lever 50 down to cause an actuation of the associated type bar of the secondary machine when the winding of the electromagnet is energized. The current passes from the winding of the electromagnet 47 to a conductor 51, thence through a conductor 52, a winding 53 of an electromagnet, whose purpose will be described further on, conductors 54, 55, 56, 57, 58, 59, 60 and 20 56, switch 17, and conductor 18 back to the line. 25

While it is not proposed to go into detail as to the dash-space arrangement for the time being, it should be noted that when coding, the dash switch of the primary machine is rendered inoperative and the space switch is effective to produce a character in the secondary machine. Thus the spaces struck when coding appear as letters in the coded message, which letters are subsequently decoded as spaces. 30

It is desirable both from the standpoint of making the code difficult to decipher and from the standpoint of saving telegraph and cable charges, to arrange the characters in five character groups. Provision is accordingly made for introducing a space automatically after every fifth keyboard operation of the primary machine when the apparatus is set for coding. It is for this purpose that the current path which has just been traced out in conjunction with the closing 35 of one character switch is caused to include the electromagnet winding 53. The armature 61 of this electromagnet is carried by a lever 62 which is pivoted at 63 and which carries a pawl lever 64. A tension spring 65 pulls one arm of the lever 62 40 down against a fixed stop 66 to maintain the armature 61 normally in an elevated position. A tension spring 67 interposed between the tail of the pawl 64 and an ear 68 on the lever 62 urges the pawl into engagement with a ratchet wheel 69. The ratchet wheel 69 is fast upon a shaft 70 and through the shaft it drives a contact ring 71. The ring is illustrated as having four contacts 72 which are adapted for successive engagement with a contact 73 at appropriate points in the 45 revolution of the ring 71. The ratchet wheel is illustrated as having twenty teeth, although obviously the number of teeth of the ratchet and the number of contacts of the segment ring may be varied, depending upon the letter grouping 50 desired and upon convenience and efficiency of design, so long as the number of ratchet teeth is a multiple of the number of ring contacts 72. At each keyboard operation of the primary machine the pawl 64 is reciprocated once and feeds 55 the ratchet wheel one tooth-space. At each fifth feeding step one of the contacts 72 wipes momentarily across the contact 73 and closes a circuit for actuating the space bar of the secondary machine. 60

65 The connection of the positive source of line current with the terminal 27 has already been described, and the connection of the negative source of current to a terminal 57^a located in the conductor 57 has already been described, and 70 75

hence for brevity these two terminals will be taken as the terminal points of the circuit. The current passes from the terminal 27 through conductor 28, conductor 74, resistance 75, and conductors 76 and 77 to the ring 71. It passes thence through one of the ring contacts 72, contact 73, conductor 78, switch 79, conductor 80, switch 81, contact 82, conductor 83, conductor 84, space bar solenoid 85, and conductor 86 to the terminal 57^a. The result is that a space is automatically introduced after each fifth character printed by the secondary machine. The switch 79 is provided to enable the feature of automatic spacing to be eliminated, if desired, and the opening of the switch does not adversely affect any of the other operating instrumentalities. When the switch is open the solenoid 53 is still energized as before and produces a rotation of the ratchet wheel 69, but the rotation of the ratchet wheel 69 is ineffective to produce any operation.

The arrangement of the coding armature or rings is illustrated more or less in detail in Figures 2 to 5. In Figure 3 a sequence of letters and other characters is indicated opposite the contacts of the outer ring 40, and the same series of characters in the opposite or inverse sequence is indicated upon the contacts of the inner ring 41. The general principle of this arrangement produces the result that when a given character is struck in coding a substitute character is produced on the secondary machine and that when the substitute character is struck in decoding the original character is produced upon the secondary machine. Since the simple alphabetical sequence indicated, however, might, if invariably employed, produce codes which could be solved by experts with considerable facility, the switchboard composed of the plugs 33 and the sockets 34 is provided in connection with the primary machine for changing the sequence of characters upon the inner ring, and the switchboard composed of the plugs 44 and the sockets 45 is provided in connection with the secondary machine for enabling the sequence of character connections upon the outer ring to be correspondingly changed so that the characters will still occur in exactly opposite order on the inner and outer rings.

The shaft 37 is mounted at its opposite ends in bearings 87 which are carried by brackets 88 supported from a frame member 89. A cylindrical insulating member 90 having segmental channels 91 formed therein embraces the shaft and supports the rings 36. Insulating rings 92 are also supported upon the cylindrical member 90 and serve to space and insulate each ring 36 from its neighbors. The rings 92 and 36 are held clamped together between an end ring 93 which is secured to the shaft 37 by a pin 94 and an adjustable end ring 95 which is threaded upon a bushing 96, the bushing being fixed to the shaft 37 by a pin 97. Sockets 98 are provided in the periphery of the ring 95 to enable it to be turned upon the bushing to clamp the rings 36 and 92 together as tightly as desired. An insulating sleeve or cylinder 99 surrounds the sleeve or cylinder formed by the rings 36 and 92, being carried by supports 100 which are mounted on the supporting frame member 89. The sleeve 99 is provided with a multiplicity of radial bores each of which contains a stationary conductive block 101 which is connected through a terminal 102 with one of the conductors 35. Each block 101 urges inward a conductive compression spring 103 which bears against a conductive plunger 104 to press a contact

ball 105 into engagement with one of the rings 36. Each ring 36 is connected through a conductor 38 with a terminal 106 provided on the insulating ring 40. The conductors 38 are carried longitudinally of the cylindrical sleeve 90 in the channels 91 thereof.

Each terminal 106 is in the form of a screw which extends into a radial passage 107 formed in the ring 40. The inner end of each screw bears against a conductive plunger 108, and this plunger in turn acts through a conductive spring 109 to urge inward a conductive plunger 110 for maintaining a contact ball 111 in engagement with the periphery of the commutator ring 41. The ring 40 is recessed to receive the commutator ring 41 and it is fixed upon a hub 112 which is made fast to the shaft 37 by a pin 113.

The commutator ring is composed of a central core portion 114 which is fixedly supported from one of the brackets 88 through an insulating plate 115. The core portion 114, in turn, supports an insulating ring 116 which surrounds the core and which divides the space surrounding the core into separate insulated compartments separated by insulating partition walls 117. The contact segments 42 are mounted one in each insulated compartment and are provided with terminal screws 118 whereby they are connected to the respective conductors 43.

It will be apparent from the description thus far given that each character switch of the primary machine communicates electrically with one of the rings 36, and thence through the associated conductor 38 and contact 39 with one of the character segments of the commutator ring 41. It will also be apparent that rotation of the shaft 37 will change the connections between the outer ring 40 and the inner ring 41 and thereby change the code for which the machine is set.

Provision is made for effecting this code changing rotation of the shaft 37 very expeditiously and efficiently and in a simple manner. To this end the shaft 37 has fast upon it a ratchet wheel 119, which is adapted to be rotated step by step by means of a pawl 120. The pawl is pivoted upon one end of a lever 121 and is urged into engagement with the ratchet wheel by means of a spring 122 which is connected between the tail of the pawl and an ear 123 on the lever 121. The lever 121 is pivoted at 124 and is normally held against a fixed stop 125 by means of a spring 126 which is connected to an arm of the lever and to a fixed frame member. The opposite arm of the lever 121 carries an armature 127 of an electromagnet 128. When the electromagnet 128 is energized, the armature is drawn down and thereby caused to operate the pawl to turn the ratchet wheel 119 a single tooth space. The ratchet teeth correspond in number and circumferential spacing to the contacts of the ring 40 so that each operation of the pawl sets up a new code.

It is important that the operator have some basis for determining and controlling the code setting. Provision is accordingly made of a disc 129 fast upon the shaft 37 and provided with a single tooth 131, the tooth being adapted to close an electric signal circuit in one code setting of the apparatus, which setting may be regarded as the zero position. The signal circuit referred to comprises conductor 14, a conductor 132, a signal light 133, a conductor 134, contacts 135 and 136, a conductor 137, conductors 59 and 60, contact 16, switch 17 and conductor 18.

As a convenient means for energizing the electromagnet 128 to operate the code setting mecha-

nism to set up any predetermined code, provision is made of a dial 138 which is the same as the usual automatic telephone dial. The dial 138 is fast upon a shaft 139 and is provided with a series of finger openings 140. Numbers running in sequence appear on a stationary disc through the openings of the dial so that the dial may be rotated any desired number of steps by inserting the finger in the opening through which the desired number is seen and turning the dial until the rotation is arrested by engagement of the operator's finger with a stationary stop 141. The dial, when operated, is returned by a spring (not shown) to the original position illustrated in Figure 1. The shaft 139 is connected through pawl and ratchet mechanism (not shown) to drive a disc 139^a counterclockwise as the dial returns to starting position. The disc 139^a is provided upon its periphery with a series of uniformly spaced knobs or pins 142. These pins are caused by rotation of the disc to travel successively over a resilient contact 143 to close a control circuit, the closing of which is effective to cause another circuit which includes the winding of the electro-magnet 128 to be closed.

The control circuit may be traced out from the terminal 27 to the terminal 57^a, the connections of these terminals with the positive and negative sides of the line having been previously described. Current flows from the terminal 27 through a resistance 144, a conductor 145 and a contact 146 through the resilient contact 143. The current passes thence through a contact 147, a switch member 148, a conductor 149, a solenoid 150, a conductor 151 and the conductor 57 to the terminal 57^a.

The solenoid 150 when energized pulls down a switch member 152 against a contact 153 and thereby closes the circuit of electromagnet 128. In this circuit the current flows from the terminal 27 through the switch member 152, the contact 153 and a conductor 154 to the winding 155 of electromagnet 128. The current passes thence through a conductor 156 to the conductor 57 and thence to the terminal 57^a. As soon as one of the pins or knobs 142 of the dial clears the contact 143 sufficiently to permit it to spring away from the contact 144, the circuit of solenoid 150 is broken, and this in turn permits the switch member 152 to move away from the contact 153 and open the circuit of the electromagnet 128 so that the pawl 120 is returned to its original position under the influence of the spring 126. Each step that the dial is turned produces a single energization of the electromagnet 128 and a single feeding step of the ratchet wheel 119. While successive operations of the dial are simply additive, any given code may be designated by any number whose digits add to the number of steps that such code is removed from the zero setting. Thus a code which is set up by rotating the ratchet wheel fifteen steps from the zero position setting might be designated as code 96 or 78 or 654 or any other such combination of digits.

The circuit of the solenoid 150 which is controlled by the dial wheel has been described as including a contact 147 and a switch member 148. The purpose of the inclusion of this switch mechanism is to enable an authorized operator to leave the machine in such condition that there is no liability of the dial being operated by one ignorant of its purpose to change the code setting. The switch member 148 is held in engagement with the contact 147 by a cam member 157, 75 which cam is mounted upon a key-controlled

shaft. The cam 157 is either of insulating material or is suitably insulated from the shaft. When the authorized operator leaves the machine, the shaft is turned to permit the contact between 147 to 148 to be broken and the key is taken out of the keyhole 158.

It is desirable when setting the machine to the zero position to be able to impart a series of single step movements to the ratchet wheel in rapid succession. For this purpose provision is made of a key switch 159 which is adapted to engage a contact 160, but which is normally held out of engagement with said contact by a spring 161. The switch member 159 is connected to conductor 146 through a conductor 162 and the contact 160 is connected to contact 147 through a conductor 163. The closing of the switch 159 has the same effect as the closing of switch 143. The switch 159 is operated like a telegraph key, the operator watching after each closing of the switch for the indicator lamp 133 to light.

Provision may also be made for causing the code to be changed automatically each time the carriage of the primary machine is returned, if desired. To this end a switch 164 operable by the carriage return key 164^a is connected in parallel with the switches 143 and 159 through conductors 162^a and 163^a. A switch 162^b interposed in the conductor 162^a, may be set to open or closed position to render the switch 164 operative or inoperative as desired.

It will be observed that in the diagrammatic representation of Figure 3 a single contact of the ring 40 is designated both by a dash and the legend "space" and that upon the ring 41 a single contact segment is designated both by a dash and the legend "space". With the particular setting illustrated in Figure 3 and from a mere inspection of said figure it might be inferred that operation either of the space bar or the dash key in the primary machine will produce the letter "B" in the secondary machine, and that operation of the letter "B" in the primary machine will produce either a dash or an actuation of the space bar in the secondary machine. This is substantially true, alternative connections being provided to cause the space bar to produce "B" and "B" to produce a dash when coding, and to cause the dash to produce "B" and "B" to produce a space when decoding. Thus when coding the dash key of the primary machine is rendered inoperative to influence the secondary machine, and the dash key of the secondary machine, but not the space bar, is rendered responsive to the letter "B" of the primary machine in the illustrative example. When decoding, the dash key of the primary machine is caused to operate the "B" key of the secondary machine, and the "B" key of the primary machine is caused to operate the space bar of the secondary machine. The letter "B" is merely used illustratively, it being the letter which happens to be involved when the code setting is that shown in Figure 3.

The space switch 19^a of the primary machine is connected through a conductor 165 to a terminal 166, and the dash switch 19^d of the primary machine is connected through a conductor 167 to a terminal 168. The space solenoid 85 of the secondary machine is connected through the conductor 84 and branch conductors 169 and 83 with terminals 171 and 82, respectively. The dash solenoid of the secondary machine is connected through a conductor 172 with a terminal 173. A switch 174 is provided having three conductive arms 175, 81 and 176 which are insulated

from one another. When the switch 174 is swung to the left (the position which it occupies when the apparatus is used for coding) the arm 175 connects the terminal 173 with a terminal 177, the arm 81 connects the terminal 82 with the conductor 80, and the arm 176 connects the terminal 166 with a terminal 178.

The operation will first be described on the assumption that the switch 174 is in the left hand or coding position. In this position the terminal 168 which is connected with the dash switch 19^d is a dead end so that the dash key of the primary machine is ineffective to produce any operation of the secondary machine. The terminal 166, which is connected to the space switch 19^s of the primary machine is also connected to the terminal 178. When the space switch of the primary machine is closed, current flows from the terminal 27 through conductors 28, 29, 31, the switch 19^s and conductor 165 to terminal 166. It passes thence through switch arm 176, terminal 178, a conductor 32^{ds}, a plug 33^{ds}, a socket 34^{ds} and a conductor 35^{ds} to a ring 36^{ds}. From this point the current flows through a conductor 38^{ds} to a contact 39^{ds} of the outer coding ring 40, thence to one of the segments 42 of the inner coding ring. The particular circuit being traced out is not shown in its entirety in Figure 1, but it will be readily understood that the segment 42 is connected through a conductor 43, a plug 44, a socket 45, and a conductor 46 with one of the character operating solenoids of the secondary machine (for example, the solenoid of letter "B"), and that the current passes from said solenoid through conductor 51, conductor 52, winding 53, and conductors 54, 55, 56 and 57 to the terminal 57^a.

Still assuming that the switch 174 is in the coding position, it will now be assumed that the letter "B" switch of the primary machine is closed by operation of the "B" key. The circuit of this switch is like that of any character switch in the primary machine, except the dash switch. With the code setting illustrated in Figure 3, the "B" switch communicates, however, with a segment 42^{ds} of the inner ring, placing such segment in circuit with the terminal 27. From the segment 42^{ds} the current flows through a conductor 43^{ds} to the terminal 177, and thence across switch arm 175 to terminal 173. From the terminal 173 the current flows through conductor 172 to the dash solenoid 47^d of the secondary machine. From the dash solenoid the current flows to the terminal 57^a along the same path already described with reference to the other character solenoids of the secondary machine.

Thus, when coding, the operation of some character of the primary machine (illustratively the letter "B") produces an actuation of the dash key of the secondary machine. At this time the terminal 171, which is connected to the space solenoid 85 of the secondary machine, is a dead end, and hence the letter "B", which is the only letter that could possibly directly actuate the space bar of the secondary machine with the code setting illustrated in Figure 3, is inoperative to influence said space bar.

The net result of the placing of the lever 174 in its left hand position is that the dash key of the primary machine cannot influence the secondary machine, the space bar of the primary machine produces the letter "B" in the secondary machine, and the letter "B" of the primary machine produces a dash in the secondary machine.

75 When the switch 174 is swung to its right hand

position, the apparatus is set for decoding, this being the only change required in order to change from coding to decoding. The switch arm 175 now bridges the gap between terminals 171 and 177, and the switch arm 176 now bridges the gap between terminals 168 and 178. The terminal 82 becomes a dead end, so that the dash solenoid of the secondary machine is taken out of operation. The terminal 166 also becomes a dead end, so that the space switch 19^s of the primary machine is taken out of operation. The dash switch 19^d of the primary machine is now connected through conductor 167, terminal 168, switch arm 176, and terminal 178 to the conductor 32^{ds}. The remaining elements of the circuit of which these elements form a part have been described in connection with the closing of the space switch of the primary machine with the apparatus set for coding. Thus, when decoding, the closing of the dash switch has the same effect upon the secondary machine as the closing of the space switch has when coding, namely, to actuate the "B" key of the secondary machine when the setting is that of Figure 3. The closing of the "B" switch of the primary machine when decoding places the "B" switch in communication with the contact 42^{ds} of the inner ring 41 and from this point the current flows through conductor 43^{ds} to terminal 171. From the latter point the current flows through switch arm 175, terminal 171 and conductors 169 and 84 to the space solenoid 85 of the secondary machine, the remainder of the circuit being the same as that already described for the space solenoid 85. The net result of the swinging of the switch to the decoding position is that the space bar of the primary machine is rendered ineffective to influence the secondary machine, the dash key of the primary machine produces a letter (illustratively the letter "B") in the secondary machine, and the "B" key of the primary machine produces an actuation of the space bar of the secondary machine.

As has been stated, the apparatus is provided with means adapting it for operation from either an A. C. or a D. C. source of current, and the description up to this point has all related to the assumption that the connections are set for D. C. operation by inserting the plug 23 between the flexible contacts 24 and 25. When the apparatus is connected to an A. C. source of current supply, the plug 23 is withdrawn, and the flexible contacts 24 and 25 assume the positions indicated in Figure 1. The A. C. current from the line now flows through the conductors 14 and 15 to a contact 179, thence through a transformer winding 180 and conductors 181, 182, 183 and 57^a from which point the circuit to the line is completed through a path already described. The conductor 15 is also connected through a conductor 184 to form a part of the plate circuit of a vacuum tube rectifier 185. The details of the rectifier are of no importance in connection with the present invention, the function of the rectifier being simply to supply direct current to the operating instrumentalities of the apparatus other than the motors. Briefly, however, the filament circuit 186 of the rectifier tube is inductively supplied with current from the transformer primary 180. The plate circuit comprises the conductor 184, the filament circuit of the rectifier, a conductor 187 which is center tapped to transformer secondary winding 188, a conductor 189, a contact 190, the flexible contact 24, and the conductor 26 to the terminal 27. The completion of the circuit from the terminal 27 to the conductor 18 has 75

been traced out through the various channels which it may follow in the description for direct current operation.

Suitable auxiliary means are provided at various points in the circuit comprising either condensers or condensers and resistances appropriately connected for preventing sparking and other purposes, but since these elements are mere details having only to do with the efficient carrying out of the purposes already described, no detailed description of them is deemed necessary.

In certain of the appended claims the term "space bar" is used for brevity. Any suitable space-producing key or keyboard member is intended to be comprehended in this term. Similarly, certain of the claims refer for brevity and clearness to the dash key of the primary machine and to the dash type of the secondary machine. This term is intended to comprehend any little used character or any character which would not necessarily have to form a significant part of an uncoded message.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

I claim:

1. In a coding and decoding machine, in combination, a manually operable primary machine, a secondary machine operable from the first, coding mechanism interposed between and interconnecting the machines, and means under the control of the operator for causing automatically measured adjustments of selected extent to be imparted instantaneously to the coding mechanism, as desired, to effect an arbitrary change of the code setting.

2. In a coding and decoding machine, in combination, a manually operable primary machine, a secondary machine operable from the first, coding mechanism interposed between and interconnecting the machines, means under the control of the operator for instantaneously adjusting the coding mechanism as desired to effect an arbitrary change of the code setting, and means for rendering the code changing means inoperative, including a key-controlled lock.

3. In a coding and decoding machine, in combination, a manually operable primary machine, a secondary machine operable from the first, coding mechanism interposed between and interconnecting the machines, means under the control of the operator for instantaneously adjusting the coding mechanism as desired to effect an arbitrary change of the code setting, and means for rendering the code changing means inoperative, including a normally open switch, means for closing said switch, and key-controlled means for rendering said switch closing means inoperative.

4. In a coding and decoding machine, in combination, a manually operable primary machine, a secondary machine operable from the first, coding mechanism interposed between and interconnecting the machines, and means under the control of the operator for instantaneously adjusting the coding mechanism as desired to effect an arbitrary change of the code setting, comprising an electromagnetic code changing means, a control circuit therefor, a switch in said circuit, a dial manually operable to select the code setting,

and a series of circuit closing members driven by the dial for closing the circuit repeatedly upon a single actuation of the dial to energize the electromagnetic code changing means a number of times corresponding to the extent of the dial operation.

5. In a coding and decoding apparatus, in combination, a primary manually operable machine including a keyboard and a space bar, a secondary machine responsive to the operation of the first and including character types and space bar mechanism, transposing means interconnecting the machines for causing operation of either a character key or the space bar of the primary machine to effect operation of a character type of the secondary machine, means for automatically operating the space bar mechanism of the secondary machine after a predetermined number of keyboard operations of the primary machine, means settable to render said automatic spacing means operative or inoperative as desired, and means settable to render the spacing mechanism of the secondary machine non-responsive to individual character key operation of the primary machine when the automatic spacing means is effective.

6. In a coding and decoding apparatus, in combination, a primary manually operable machine including a keyboard and a space bar, a secondary machine responsive to the operation of the first and including character types and space bar mechanism, transposing means interconnecting the machines for causing operation of either a character key or the space bar of the primary machine to effect operation of a character type of the secondary machine, means for automatically operating the space bar mechanism of the secondary machine after a predetermined number of keyboard operations of the primary machine, means settable to render said automatic spacing means operative or inoperative as desired, and means automatically effective to render the space bar mechanism of the secondary machine non-responsive to individual character key operation of the primary machine when the automatic spacing means is effective.

7. In a coding and decoding apparatus, in combination, a primary manually operable machine including a keyboard and a space bar, a secondary machine responsive to the operation of the first and including character types and spacing mechanism, transposing means interconnecting the machines for causing operation of either a character key or the space bar of the primary machine to effect operation of a character type of the secondary machine, means for automatically operating the spacing mechanism of the secondary machine after a predetermined number of keyboard operations of the primary machine, and means settable to one position simultaneously to render the automatic spacing means inoperative and to break the operating connection from the space bar of the primary machine to the secondary machine, and settable to another position simultaneously to render the automatic spacing means operative and to re-establish the operating connection from the space bar of the primary machine to the secondary machine.

8. In a coding and decoding apparatus, in combination, a primary manually operable machine including a keyboard and a space bar, a secondary machine responsive to the operation of the first and including character types and space bar mechanism, transposing means inter-

connecting the machines for causing operation of either a character key or the space bar of the primary machine to effect operation of a character type of the secondary machine, means for 5 automatically operating the space bar mechanism of the secondary machine after a predetermined number of keyboard operations of the primary machine, and means settable to one position to simultaneously render the automatic spacing 10 means inoperative and the space bar mechanism of the secondary machine directly responsive to keyboard operation of the primary machine, and to break the operating connection from the space bar of the primary machine to the secondary 15 machine, and settable to another position simultaneously to render the automatic spacing means operative and the space bar mechanism of the secondary machine non-responsive to direct character key operation of the primary machine, 20 and to re-establish the operating connection from the space bar of the primary machine to the secondary machine.

9. In a coding and decoding apparatus, in combination, a primary manually operable machine having a keyboard including character keys and a space bar, a secondary machine including character keys and spacing mechanism, transposing means interconnecting the machines to operate the secondary machine from the primary machine to cause the writing of a message on the primary machine, including all of the characters and spaces thereof, to produce in the secondary machine a code message in which each of the characters and spaces of the uncoded message 35 is replaced by a character, said means including mechanism for automatically introducing spaces to divide the code characters into equal groups, and means instantaneously settable to change the mode of operation of the apparatus for decoding, to cause the writing of the coded message on the primary machine, including all of the characters and spaces thereof, to produce in the secondary machine an exact reproduction of the uncoded message with all 40 of the original characters and spaces correctly included, and the automatically introduced spaces eliminated.

10. In a coding and decoding machine, in combination, a primary machine having a keyboard including character keys and a space bar, a secondary machine including character types and a spacer, coding means connecting the machines for in general causing any keyboard operation of the primary machine to effect the printing of a 55 substitute character in the secondary machine, but including means for making the space bar and the dash key of the primary machine, alternatively effective for coding and decoding, respectively, to produce the same character operation of the secondary machine.

11. In a coding and decoding machine, in combination, a primary machine having a keyboard including character keys and a space bar, a secondary machine including character types and a spacer, coding means connecting the machines for in general causing any keyboard operation of the primary machine to effect the printing of a substitute character in the secondary machine, but including means for making the dash type and 65 the spacer of the secondary machine alternatively responsive, for coding and decoding, respectively, to the same character key operation of the primary keyboard.

12. In a coding and decoding machine, in combination, a primary machine having a keyboard

including character keys and a space bar, a secondary machine having operating instrumentalities including character types and a spacer, coding means connecting the machines effective in general to reciprocally pair the keyboard members of the primary machine and the operating instrumentalities of the secondary machine so that operation of any selected key of the primary keyboard operates a particular substitute operating instrumentality of the secondary machine, and 10 operation of the primary key corresponding to the substitute operating instrumentality operates an operating instrumentality of the secondary machine corresponding to the key originally operated, but in which provision is made of adjustable means for alternatively producing the same code character by the space bar when coding and by the dash key when decoding, and for alternatively producing dashes by operation of a particular key when coding and spaces by operation 15 of the same key when decoding.

13. In a coding and decoding machine, in combination, a manually operable primary machine, a secondary machine operable from the first, coding mechanism interposed between and interconnecting the machines, and means under the control of the operator for instantaneously adjusting the coding mechanism as desired to effect an arbitrary change of the code setting, comprising 20 an electromagnetic code changing means, a control circuit therefor, a switch in said circuit, a dial manually operable to select the code setting, and a series of circuit closing members driven by the dial for closing the circuit repeatedly upon a single actuation of the dial to energize the electromagnetic code changing means a number of times corresponding to the extent of the dial operation, means for indicating a datum or zero code setting, and a separate manually operable circuit closing switch for operating the electromagnetic 30 code changing means step by step to the zero setting.

14. In a coding and decoding machine, in combination, a manually operable primary machine, a secondary machine operable from the first coding mechanism interposed between and interconnecting the machines, means under the control of the operator for instantaneously and automatically adjusting the coding mechanism to a selected extent as desired to effect a selected arbitrary change of the code setting, and means responsive to a key operation of the primary machine to change the code setting automatically 40 from time to time.

15. In a coding and decoding machine, in combination, a manually operable primary machine, a secondary machine operable from the first, coding mechanism interposed between and interconnecting the machines, means under the control of the operator for instantaneously adjusting the 50 coding mechanism as desired to effect an arbitrary change of the code setting, and means responsive to the carriage return operation of the primary machine to change the code setting automatically.

16. In a coding and decoding machine, in combination, a manually operable primary machine, a secondary machine operable from the first, coding mechanism interposed between and interconnecting the machines, means under the control of the operator for instantaneously adjusting the 60 coding mechanism as desired to effect an arbitrary change of the code setting, means responsive to the carriage return operation of the primary machine to change the code setting automatically, and means for rendering said automatic code 70 75

- changing means operative or inoperative as desired.
17. In a coding or decoding apparatus, in combination, a primary machine having a keyboard, a secondary machine having operating instrumentalities, and coding means connecting the machines to control operation of the secondary machine from the primary machine comprising a series of electrical circuits each adapted to be selectively closed for a predetermined time by keyboard operation of the primary machine, each circuit including a power operated switch under the control of a keyboard member of the primary machine and mechanical power means included in the primary machine for mechanically closing each switch in a positive and uniform manner and for a predetermined period in response to keyboard operation.
18. In a coding and decoding apparatus in combination, a power operated primary machine having a keyboard and writing instrumentalities, a secondary machine having writing instrumentalities, and coding means connecting the machines to control the operation of the secondary machine from the primary machine comprising a series of electric circuits each including a switch, the primary machine including a series of power operated members each individual to one of the

keyboard members and adapted to be mechanically tripped by the latter for operating one of the writing instrumentalities of the primary machine and effective when tripped to close one of the switches in a positive and uniform manner 5 and for a predetermined period.

19. In a coding and decoding machine, in combination, a manually operable primary machine, a secondary machine operable from the first, coding mechanism interposed between and interconnecting the machines, and means responsive to mechanism controlled in accordance with the arbitrary and irregular arrangement of grouping of words of a message to effect automatically the code setting between the said machines. 10 15

20. The invention set forth in claim 19 in which the last mentioned means comprises the carriage return mechanism.

21. A coding and decoding machine comprising a manually operable primary machine, a secondary machine operable from the first, coding means comprising a single movable circuit changing device interposed between and interconnecting the machines, and an electrical control circuit under control of the primary machine to control 20 25 the positioning of the said coding means at irregular and arbitrary intervals.

WALTER S. LEMMON.
